4 Claims. (Cl. 83—540)

This invention relates to a toolholder for multiple punch presses. Multiple punch presses of various types are already known to the art. A feature which is common to all these multi-punch presses is the provision of a major number of tools in a rotatable tool head to permit different holes to be punched, for instance, into sheet metal blanks without the need of exchanging the tools. Generally, such multiple punch presses are also equipped with a compound slide table which permits punching to proceed without previously marking out the work. In other types of multiple punch presses the tools are held in a segment-shaped head which is rotatable about a vertical axis. However, the tools may be held in a head of some other shape, provided means are provided for indexing the head.

In known multiple punch presses the rotatable die and punch plates containing the tools or a corresponding toolholder are mounted in the machine frame. This machine frame must be constructed to withstand the reactive punching thrusts, and if the cross sections used in the construction of the frame are to be within economical limits, the frame is subjected to elastic deformation which frequently exceeds permissible limits. This elastic deformation affects the angular position of the arms of the frame and hence causes the punches to be deflected out of the theoretical perpendicular in which the stroke of the punch should take place. This displacement of the punches may lead to inaccurate cutting. For accurate work the cutting clearance between punch and die must be uniform. Unless the punch enters the die centrally this clearance will be greater on one side than on the other. The resultant cut will not then be satisfactory and the life of the tools will be greatly reduced owing to increased wear.

The invention which will be hereafter described avoids the afore-mentioned difficulties.

The invention consists in that a punch press with a C-type frame comprising a tool head for one or more tools in the gap of the frame is provided with a special bearing frame located without constraint in the gap of the C-shaped main frame in such manner that any deformation of the main frame cannot affect the bearing frame. In other words the proposed arrangement is such that deformation of the main frame cannot generate stresses in the bearing frame. The bearing frame is therefore secured in the gap of the main frame when viewed from the side at any suitable point, i.e. at a point which cannot transmit deformations of the main frame to the supplementary bearing frame. However, it is primarily intended to apply the invention to multiple punch or indexing tool head presses. According to the invention the C-shaped bearing plate is provided in the gap of the main frame and secured preferably by bolting its lower limb to the lower part of the main frame. The lower and upper limbs of the bearing frame contain the pivot pins for punch and die plates. Naturally, segment-shaped plates may take the place of completely circular punch and die plates.

The accompanying drawings illustrate an embodiment of the invention in the case of a punch press with a rotatable tool head. In the drawings

FIGURE 1 is a side elevation of the press showing only those parts which are relevant to the invention, and

2

FIGURE 2 is a section of the machine taken on the line I-II in FIGURE 1.

Located in the C-shaped frame 1 of the machine is a likewise C-shaped bearing frame 2 which is gapped on the same side as the main frame and therefore has the shape of an overturned U when viewed from the side. Only the bottom limb of this bearing frame is bolted at 3 to the outer walls of the main frame 1 above the table. The bearing frame carries the pins 4 and 5 about which the two parallel rotatable tool plates 6 and 7 can index. The punching pressures or rather the reactive thrusts are transmitted by ram 8 through the toggle lever system 9 to pin 10 with such toggle lever system being driven by push rod 18 and are thus taken up by the outer main frame 1 of the machine. Naturally a toggle lever system may be replaced by an eccentric or the thrust may be generated by a hydraulically operable ram cylinder. The bearing frame 2 does not therefore participate in taking up the thrust and it is not subject to detectable deformation so that the punches retain their correct positions in relation to the dies in the lower plate. The thrust generated when stripping the perforated blank, which may be equal to about 10% of the thrust required for punching, is transmitted by the stripper plate 11, the punch plate 7 and the backing pin 12 directly to the main frame 1 of the press. The described arrangement thus solves the problem of providing a support for the punch or toolholder which is not affected by the action of the reactive forces on the machine frame 1 engendered during the punching and stripping operations.

The drawings show the tools 14 in the upper plate, the tools having a hemispherical head 15 which engages a recess 16 in ram 8 for the central transmission of thrust. The machine frame 1 is mounted on a pedestal 17, being secured thereto by screws 19.

In the illustrated embodiment of a punch press with a rotatable tool head the main frame 1 consists of two upright side plates of considerable height located in two parallel planes. This arrangement permits the bearing frame 2 to be interposed between the two spaced plates of the main frame 1 and to be secured exclusively by bolts 3 which connect the lower limb of the bearing frame 2 with the bottom part of the main frame. The main frame includes a slideway 20 between the two side plates thereof and the ram is slidably disposed in such slideway. Alternatively the bearing frame might be located in a recess of the main frame in such manner that any deformation of the main frame 1 cannot affect the bearing frame.

50 I claim:

1. In a punch press, a C-shaped main frame, a rotatable die plate mounted in the gap of the frame, a bearing frame located in the gap of the main frame, the bearing frame being unstressed by deformation of the main frame, a rotatable punch plate supported by the bearing frame in the gap of the main frame, a plurality of punches slidably disposed in the punch plate, and a ram slidably disposed in the main frame and engageable with any selected one of the punches to operate the latter so that only forces in an axial direction are transmitted by the ram and punch with all forces generated during operation of a punch being absorbed directly by the main frame and the bearing frame being unstressed by such forces.

65 2. In a punch press, a C-shaped main frame, a bearing frame located without restraint in the gap of the main frame, a rotatable die plate supported by the bearing frame, a rotatable punch plate supported above the die plate by the bearing frame, a plurality of punches slidably disposed in the punch plate, and a ram slidably disposed in the main frame and engageable with any selected one of the punches to operate the latter so that only forces

in an axial direction are transmitted by the ram and punch with all reactive forces generated during operation of a punch being transmitted by the ram to the main frame and the bearing frame being unstressed by such forces and being unstressed by deformation of the main frame.

3. In a punch press, a C-shaped main frame, a C-shaped bearing frame located in the gap of the main frame, the bearing frame having a lower limb fastened to the lower limb of the main frame and being otherwise unrestrained, a rotatable die plate supported in the said gap by the lower limb of the bearing frame, a rotatable punch plate supported in the gap and above the die plate by the upper limb of the bearing frame, a plurality of punches slidably disposed in the punch plate, and a ram slidably disposed in the main frame and engageable with any selected punch to operate the latter so that only forces in an axial direction are transmitted by the ram and punch with all forces generated during operation of a punch being transmitted to the main frame and the bearing frame being unstressed by such forces.

4. In a punch press, two spaced parallel C-shaped side plates constituting a main frame, a pivot pin disposed between the upper limbs of the side plates, a C-shaped bearing frame disposed between the side plates, the bearing frame having its lower limb bolted to the lower limbs of the side plates and being otherwise unrestrained, a rotatable die plate supported within the gap of the main frame by the lower limb of the bearing frame, a rotatable

5 punch plate supported within the gap by the upper limb of the bearing frame, a backing pin bearing between the upper limb of the main frame and the top of the punch plate, a plurality of punches slidably disposed in the punch plate, a ram slidably disposed in the said main frame and engageable with a selected punch to operate the latter, a toggle lever system coupling the ram to the said pivot pin, and means for flexing the toggle lever system to actuate the ram so that only forces in an axial direction are transmitted by the ram and punch with all reactive forces generated during operation of a punch being transmitted by way of the ram, backing pin, toggle lever system and pivot pin to the main frame.
